INTERCHANGEABLE DIE COLLET

Karl A. Kuhn, Greenfield, Mass., assignor to
Greenfield Tap and Die Corporation, a corpora-
tion of Massachusetts

Application July 23, 1937, Serial No. 155,162

5 Claims. (Cl. 10—116)

This invention relates to dies and is especially directed to a die collet adapted to hold in accurately clamped position dies of various sizes.

The general purpose of the invention is to provide a collet adapted for the interchangeable mounting of dies of the sectional type in a wide range of sizes, and particularly to provide means for clamping in the collet dies varying in thickness.

10 Other objects and advantages will appear from the following specification taken in connection with the accompanying drawing, in which

Figure 1 is a top plan view of an assembled collet;

15 Figure 2 is a transverse section on line 2—2 of Figure 1;

Figure 3 is a transverse section on line 3—3 of Figure 1;

20 Figure 4 is a sectional view similar to Figure 3 illustrating another type of interchangeable clamping elements;

Figure 5 is an expanded view of the construction shown in Figure 4;

25 Figure 6 is a section similar to Figure 3 of another arrangement to the interchangeable clamping structure; and

Figure 7 is an expanded view of the clamping members of Figure 6.

30 The collet is preferably of the cylindrical type adapted to fit into standard sockets in die stocks and the like. The body 11 is provided with a cylindrical concentric recess 12 forming a cylindrical side wall 13 and a bottom 14 having a central opening 15 of appropriate size and contour for the passage of the work and the discharge of chips.

35 The collet is particularly adapted to hold in clamped position a die of the sectional type including opposed jaws symmetrically located with respect to the die axis and capable of longitudinal adjustment. An appropriate embodiment is illustrated, comprising two die jaws 16 having beveled side faces 17, adapted to rest on the bottom 14 and to be adjusted longitudinally as by screws 18 in the body 11.

40 The die jaws 16 are clamped in body 11 by clamping segments 19 fitting accurately against wall 13 of the recess 12 at opposite sides and provided with beveled inner faces 20 at the same angle as the effective side faces 17 of die section 16. The segments 19 are held in clamping position by screws 21 extending through the bottom of the body 11. Segments 19 are accurately positioned and shaped to clamp the die jaws 16

in accurate alignment with each other and the axis of the work.

Die jaws 16 may be made in various thicknesses; and an arrangement is provided whereby such jaws may be interchangeably clamped in the same body 11. One construction for this purpose is shown in Figures 4 and 5, and comprises an interchangeable bottom plate 22 fitting accurately on the bottom 14 and provided with a central recess 23 registering with recess 15. 5 Clamping segments 24 are similar in shape and arrangement to segments 19 except for decreased thickness corresponding to the reduced thickness of die jaws 25 in comparison with jaws 16. 10 Clamping screws 26 extend through the bottom 14 of body 11 and bottom plate 23 into threaded engagement with clamping segments 24, arranged so that when the die jaws 25 are in position and screws 26 are tightened, said jaws will be held firmly in accurately aligned position between segments 24 and against the bottom plate 22. 15

With this construction it will be apparent that for each thickness of die jaws 25 a corresponding bottom plate 22 and segments 24 may be provided, permitting the use of the body 11 and the standard die stocks or the like for a substantial range of die thicknesses, while maintaining flush surfaces at the top and bottom of the collet after the die jaws and clamping structure have been 20 assembled therein. 25

Another arrangement for the same purpose is illustrated in Figure 6. It is similar in construction to the form shown in Figure 4, except that one of the clamping segments 24 is fixed to the 30 bottom plate 22, and preferably is integral therewith, forming a composite clamping member 27 35 and reducing the number of parts.

The parts are constructed and arranged to facilitate great accuracy in construction and alignment, and to provide firm positive clamping of die jaws of various sizes. They are designed for ready manufacture on standard machines. The preferred embodiments illustrated herewith have been shown to scale, though various modifications are possible within the scope of the invention as set forth in the claims. 40 45

I claim:

1. A die collet comprising a body having a die receiving recess and an interchangeable die-hold- 50 ing unit in the recess, said unit comprising a removable die seat in the bottom of the recess, a die clamp member on the seat at one side of the recess, a separable cooperating die clamp member above the seat at the opposite side of 55

the recess, and means for holding said members and seat in die-holding position in the recess.

2. A die collet comprising a body having a die receiving recess, and an interchangeable die-holding unit in the recess, the unit comprising a removable die seat on the bottom of the recess, a die clamp member on the seat at one side of the recess, having a beveled face positioned to engage one side of a die element, a separable co-operating die clamp member above the seat at the opposite side of the recess and having a beveled face positioned to engage the other side of a die element, and means including an element engaging the separable member for clamping said unit in operative die-holding position.

3. An interchangeable die-clamping unit comprising a body of circular disk shape having a cylindrical side wall or flange and a seat for the bottom of a die element, a die clamping member mounted on one side of the seat within said side wall and arranged to engage one side of a die element, a separable member at the other side of the seat within said side wall arranged to engage the opposite side of a die element, and means for holding the separable member in die-clamping relation to the other member and seat comprising retaining means extending upward

through said body from the lower surface thereof.

4. An interchangeable die-clamping unit comprising a body of circular disk shape having a cylindrical side wall or flange and a die seat 5 adapted to engage the bottom of a die element, a die clamping member integral with the seat within said side wall and arranged at one side thereof in position to engage a side of a die element, a separable die clamp member at the other 10 side of the die seat within said side wall in position to engage the other side of a die element, and means for holding the separable member in die-clamping relation to the other member and seat comprising retaining means extending up- 15 ward through said body from the lower surface thereof.

5. A die collet comprising a body having a die receiving recess, and an interchangeable die-holding unit mounted in the recess, said unit 20 comprising a seat in the bottom of the recess, a die clamp member mounted on the seat at one side, and a co-operating die clamp member removably mounted above the seat at the other side by screw means engaging the body. 25
